UNITED STATES PATENT OFFICE

2,622,349

TRACTOR ROAD SCRAPING APPARATUS

Carl Kinnan, Morgantown, W. Va.

Application April 5, 1948, Serial No. 19,078

4 Claims. (Cl. 37—156)

1

My invention relates to improvements in tractor road scraping apparatus, the primary object in view being to provide road scraping apparatus of the scraper blade type adapted for attachment to the hydraulic power lift mechanism of tractors of commerce for raising and lowering of the scraper from and into operative scraping position by said mechanism, as occasion may require, and which is designed to provide for lateral swinging of the scraper into selected oblique positions relative to the path of travel of the tractor, to facilitate scraping under different operating requirements, and also for reversing of said scraper to adapt the apparatus for use as a bulldozer when the tractor is backed.

Other and subordinate objects, within the purview of my invention, together with the precise nature of my improvements will be readily understood when the succeeding description and claims are read with reference to the drawings accompanying and forming part of this specification.

In said drawings:

Figure 1 is a fragmentary view in side elevation of my improved road scraping apparatus in a preferred embodiment thereof attached to the hydraulic power lift mechanism of a tractor;

Figure 2 is a fragmentary view in plan of the same, partly broken away;

Figure 3 is a fragmentary view in rear elevation of the same;

Figure 4 is a fragmentary view in plan drawn to a larger scale;

Figure 5 is a detailed view in transverse section taken on the line 5—5 of Figure 2 and drawn to a larger scale;

Figure 6 is a view in vertical transverse section taken on the line 6—6 of Figure 2 and drawn to a larger scale;

Figure 7 is a view in perspective of the turntable drawn to a smaller scale.

Describing my invention in detail, with reference to the drawings by numerals, my improved road scraping apparatus has been shown, for the purpose of illustration, as attached to the hydraulic power lift mechanism of a well-known type of tractor illustrated conventionally, the numeral 1 designating the rear traction wheels, 2 the rear differential housing, 3 the usual pair of rear power lift side arms vertically swingable on pivots 4 on said housing, 5 the usual hydraulically operated cranks connected by links 6 to said arms 3 to raise and lower the same, and 7 the usual pivoted rocker on said housing 2 for operating a spring pressed plunger 8 under overload on the power lift mechanism to cause said

2

arms 3 to be swung upwardly. Such power lift mechanism is well-known in the art and, therefore, a detailed showing and description thereof is not deemed to be necessary to a proper understanding of the same and the relation of my improved apparatus thereto. For a detailed disclosure of such power lift mechanism, reference may be had to U. S. Letters Patent No. 2,118,180.

According to my invention, a turntable 9 is provided between the rear ends of the side arms 3 comprising an annular flat band rim 10 with a diametrical bar-like web 11 adapted to extend transversely of said arms 3. A mounting for the turntable 9 suspends the same from the rear ends of said arms 3 for tilting vertically about an axis transverse to the path of travel of the tractor, and for oscillation about the vertical axis of the turntable.

The mounting for the turntable 9 comprises a transverse bar 12 overlying said web 11 diametrically of the turntable 9 and to which said turntable is pivoted for oscillation, substantially horizontally, by a king-bolt 13 extending through said web 11 and bar 12 in the axis of the turntable. Pairs of cross-bars 14, 15 welded, as at 16, on top of said bar 12 surmount the same upon opposite sides of the king-bolt 13 for a purpose presently seen. A pair of aligned bars 17 spaced apart end to end upon opposite sides of said king-bolt 13 are welded, as at 18, on top of the pairs of cross-bars 14, 15 parallel with the bar 12 with outer ends fitted between the rear ends of the side bars 3 and pivoted thereto by horizontal bolts 19. As will be seen, the described mounting for the turntable 9 provides for clear access to the king-bolt 13 for tightening or other purposes. A pair of scraper carrying arms 20 with downturned rear ends 21 extend rearwardly of said turntable 9 beneath the same and from opposite sides thereof and opposite ends of said web 11.

Means are provided for oscillating the turntable 9 about the king-bolt 13, as follows. A bifurcated head block 22 above the turntable 9 is swingable laterally on a clevis 23 to which said block is pivoted by a bolt 24 axially aligned with the turntable 9. The clevis 23 is pivoted by a transverse bolt 25 for vertical swinging on the rear end of a turnbuckle compression rod 26 having its front end pivoted by a transverse pin 27 to the rocker 7 so that said rod 26 is vertically swingable. A pair of connecting bars 28 extend downwardly and forwardly from opposite sides of the head block 22 to the front of the rim 10 of the turntable 9 and are secured thereto, as

at 29. A pair of similar bars 30 similarly extend from opposite sides of said head block 22 to the scraper carrying arms 20 and are secured thereto, as at 31, with upper spaced apart ends 32 extending above said block 22. Bolts 34 secure said bars 28, 30 to the head block 22.

A hand lever 35 is pivoted by a bolt 36 between the upper ends 32 of the bars 30 to extend forwardly within easy reach of the driver's seat, not shown, of the tractor, or to be swung vertically into a rearwardly extending position, said lever in either position providing for oscillating the bars 28, 30 and the head block about the bolt 24 to oscillate the turntable 9 about its axis as will be clear.

As will be seen, the described means for oscillating the turntable 9 provides for the turn-buckle compression rod 26 functioning together with the side arms 3 in the manner of a parallel link motion for maintaining the turntable 9 substantially horizontal at all times. The turn-buckle construction of the compression rod 26 provides for lengthening or shortening of said rod to tilt said turntable 9 about the bolts 19 and relative to the side arms 3 out of the horizontal as may be required.

Locking means provide for retaining the turntable 9 in different set oscillated positions and will now be described. A pair of horizontal lock bolts 36 are slidably mounted at opposite sides of the turntable 9 in the pairs of cross-bars 14, 15 to extend along relatively opposite sides of the bar 12 for projection into circumferentially spaced apertures 37 in the rim 10 of the turntable 9. Coil springs 38 suitably arranged on the lock bolts 36 to bear against collars 39 on said bolts act to project said bolts into apertures 37 registered with said bolts.

A horizontal latch bolt retracting lever 40 is pivoted in horizontal position on the king-bolt 13 to extend rearwardly over the bar 12 and be swung horizontally, and is operatively connected to inner ends of said latch bolts 36 by bolts 41 and slots 42 so that swinging of said lever 40 in one direction will cause retraction of the latch bolts 36 and unlock the turntable 9. A pull cable 43 is connected to the latch bolt retracting lever 40 and trained around a pulley 44 to be extended forwardly to within easy reach from the driver's seat of the tractor. The pulley 44 may be mounted on an arm 45 extending rearwardly from one of the bars 17.

A double edge, concave, scraper 46 is provided on the scraper carrying arms 20 and is preferably formed of twin blade sections 47 bolted, as at 48, to a concave face channel beam 49. Pairs of bars 50 extending from plates 51, bolted as at 52, to the channel side of said beam 49 straddle the rear ends 21 of the scraper carrying arms 20 and are pivoted thereon, as at 53, so that the scraper 46 is swingable under said ends 21 into a forwardly facing position in front of said ends, for scraping when the tractor is driven forwardly, or, into a rearwardly facing position in the rear of said ends 21, as shown by dotted lines, in Figure 6, to function as a scraping bulldozer when the tractor is reversed. In either of the described positions of the scraper 46, right angled edge lugs 54 on opposite side edges of the channel beam 49 engage the ends 21 of said arms 20 and establish the position of the scraper.

Manually releasable latch means is provided for automatically latching the scraper 46 in either of the described positions thereof as follows. A pair of substantially segmental scraper latch plates 55 are provided alongside the rear

ends 21 of the scraper carrying arms 20 on opposite ends of a horizontal, transverse rock shaft 56 journalled in said ends 21, the arrangement being such that upon rocking of said shaft 56 in opposite directions, said latch plates 55 will be correspondingly swung, in unison, into two opposite latching positions, in one of which hook lugs 57 thereon will hook over the lugs 54 on one side edge of the channel beam 49 and latch the scraper 46 in forwardly facing position, whereas, in the other position of the latch plates 55 similar hook lugs 58 thereon will hook over the lugs 54 on the other side edge of the beam 49 and latch the scraper 46 in rearwardly facing position.

Coil springs 59 are connected to the ends 21 of the scraper carrying arms 20, as at 60, and to said latch plates 55, as at 61, to swing said latch plates 55 past a dead center position, relative to the connections of said springs 59, into either of the latching positions thereof which are established by stop pins 62 on said ends 21. The hook lugs 57, 58 are formed with cam edges 63, 64 so that when the scraper 46 is swung into either forwardly or rearwardly facing position, said edges 63, 64 will coat with appropriate lugs 54 to cam the latch hook lugs 57, 58 upwardly for snap action latching engagement, under the urge of the springs 59, with the appropriate lugs 54.

For unlatching the scraper latch plates 55, a bell-crank 65 is fixed on the rock shaft 56 with pull cables 66, 67 attached to opposite ends thereof and trained over side by side pulleys 68, 69 on one scraper carrying arm 20, said cables being further arranged to extend forwardly to within easy reach from the driver's seat of the tractor for pull on said cables alternately to rock the rock shaft 56 in opposite directions and swing said latch plates 55 in opposite directions from either latching position past dead center position to be moved by the coil springs 59 into the opposite latching position thereof.

The operation of the described invention will be readily understood. The turntable 9 with the scraper carrying arms 20 and the scraper 46 may be raised and lowered by the hydraulic lift mechanism of the tractor from and into operative scraping position, as desired. When the turntable 9 is raised, and unlocked in the manner already described, it may be oscillated, or revolved, substantially horizontally into different set angular positions to position the scraper 46 in different positions oblique to the path of travel of the tractor, either forwardly or rearwardly, for instance the position shown in dotted lines in Figure 2. In the different set positions thereof, the turntable 9 may be automatically locked, by releasing the pull cable 43, through projection of the lock bolts 36 by the springs 37. By adjusting the compression rod 26, the turntable 9 may be tilted about an axis transverse to the tractor, in the manner described, to vary the pitch of the scraper blade sections 47. By unlatching the scraper latch plates 55, in the manner described, to unlatch the scraper 46 in its forwardly facing position, and causing said plates 55 to swing into an opposite latching position, the scraper 46 may be lowered to the ground and caused to roll along the same, when the tractor is driven forwardly, to thereby assume rearwardly facing position in which the same will be automatically latched by said latch plates 55. Conversely, with the scraper 46 in rearwardly facing position, and the latch plates 55 unlatched and swung into an opposite latching

position, the scraper 46 may be caused to roll along the ground, when the tractor is backed, to thereby assume forwardly facing position in which the same will be automatically latched by the latch plates 55, as described.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

Having described the invention what is claimed as new is:

1. The combination with a tractor having a pair of rear power lift arms, of a transverse bar between said arms, an annular band surrounding said bar and having a diametrical web, a pivot member extending centrally through said bar and web and suspending said band for oscillation about said pivot, a pair of spaced apart bars overlying the transverse bar longitudinally thereof upon opposite sides of said pivot member and rigidly connected to said transverse bar with corresponding ends pivoted to said arms to pivotally suspend said transverse bar between said arms for tilting on said arms to correspondingly tilt said band, a scraper, means mounting said scraper to said band for oscillation and tilting thereby in reversed positions, and means to lock said band against oscillation comprising a horizontal lever pivoted on said pivot member between said pair of bars, and a pair of lock bolts slidably mounted to said transverse bar at opposite sides thereof and slidably and pivotally connected to said lever at opposite sides of said pivot member.

2. The combination of claim 1 wherein said last means further includes a bracket arm on one bar of said pair having a pulley thereon at one side of said lever and a pull cable connected to said lever and trained over said pulley to extend forwardly to said tractor.

3. The combination with a tractor, of a scraper, means to mount said scraper on said tractor comprising a pair of rearwardly extending arms

attached to said tractor and having downturned rear ends, a scraper carrying bar having a pair of end lugs on opposite longitudinal edges thereof, laterally extending mounting bars for said scraper carrying bar fixed to opposite ends thereof and pivoted to said downturned ends for swinging to swing said carrying bar forwardly and rearwardly of said downturned ends, respectively, latch means for releasably retaining said carrying bar in forwardly and rearwardly swung positions comprising a rock shaft journaled in said downturned ends, a latch plate fast on one end of said shaft alongside of one of said rear ends for rocking by said shaft past an intermediate position, spring means connected to said plate and said rear end for swinging said plate into opposite positions past intermediate position, nooks on said plate for engagement with said lugs in the opposite positions of said plate when said carrying bar is in its forwardly and rearwardly swung positions, and manual means for rocking said shaft in opposite directions to correspondingly swing said plate past intermediate position including pull cables extending to said tractor.

4. The combination according to claim 3 wherein said last-named means further includes oppositely extending cranks on said shaft connected to said pull cables.

CARL KINNAN.
